By Clarence A. O'Brien
Attorney

UNITED STATES PATENT OFFICE.

EDWARD GIOSEPH MARINETTI, OF RIVERSIDE, RHODE ISLAND.

SHOE CLOSURE ATTACHMENT.

Application filed June 29, 1927. Serial No. 202,288.

The present invention relates to an attachment for shoes to take the place of the usual lacing and tongue structure, and has for its principal object to provide a device of this nature which is exceedingly simple in its construction, convenient, inexpensive to manufacture, strong and durable, easy to manipulate, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is an elevation of the attachment showing the same in a closed position.

Figure 2 is a similar view showing the same in an open position.

Figure 3 is a section taken substantially on the line 3—3 of Figure 1.

Figure 4 is a perspective view of the relatively rigid member showing parts in disassembled relation thereto, and

Figure 5 is a perspective view of one of the top sleeve forming elements.

Referring to the drawing in detail it will be seen that the numeral 5 denotes a shoe upper having the usual slit or opening 6 provided therein. A plurality of split sleeves 7 are formed with ear extensions 8 riveted or otherwise secured as at 9 to the upper 5 so as to provide two series of sleeves, the sleeves in each series being alined with one another. The lowermost sleeves are formed with inwardly extending stop pro-

jections 10.

The numeral 11 denotes a relatively rigid plate member which is bent along two longitudinal lines, one to each side of the center longitudinal line as at 12 to overhang the intermediate portion and then being reversely bent to provide side wings 14 to which are secured extensions 15 of sleeves 16, these sleeve members 16 are slideable through the split sleeves 7. The uppermost sleeve members 16 have their upper ends pointed as is indicated at 17. The plate 12 tapers downwardly and has stops 18 on the upper portions of the wings 14 to abut the snap lugs 10 when the device is disclosed as is shown in Figure 2, that is in an open

position. A cord 19 is trained through the sleeves 16 and has its extremities fixed in the upper sleeves 16, thereby forming a loop at the lower end indicated specifically by the numeral 19' which functions as handles 60 in order that the device may be pulled downwardly to an open position. A loop 20 is attached to the upper end of the plate 11 by suitable fastening means and simulates an ordinary shoe tongue and functions as a 65 handle in order that the device may be pulled upwardly to a closed position. The cord 19 gives the device the desired flexibility for comfort and the like. The loop 19' not only functions as a handle for pulling the 70 device down but permits the upward movement thereof. The extensions 15 of the sleeves 16 are preferably held in place by eyelet rivets denoted by the numerals 23 for the purpose of forming eyelets in order that 75 lacing 24 may be trained therethrough in simulation of the ordinary lacing now in common use upon shoes and the like.

It is thought that the construction, convenience in operation of the device will now 80 be quite apparent to those skilled in this art without a more detailed description thereof. The present embodiment of the invention has been disclosed in detail merely by way of example since in actual practice it attains 85 the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described the invention, what 95 I claim as new and desire to secure by Letters Patent is:—

1. In a structure of the class described, two series of sleeves, the sleeves in each series being alined with each other and having ears adapted to be riveted to the upper of a shoe, a relatively rigid member, sleeves fixed to the relatively rigid member, a series on each side thereof, a cord trained through the last mentioned sleeves so that said last mentioned sleeves and the cord may slide in the first mentioned sleeves, said first mentioned sleeves being split, the lower two of the first mentioned sleeves being provided with stop lug extensions, and stop members 100 105 110

on the relatively rigid member for engagement therewith to limit the downward movement of the relatively rigid member.

2. In a structure of the class described, 5 two series of sleeves, the sleeves in each series being alined with such other and having ears adapted to be riveted to the upper of a shoe, a relatively rigid member, sleeves fixed to the relatively rigid member, a series on 10 each side thereof, a cord trained through the last mentioned sleeves so that said last mentioned sleeves and the cord may slide in the first mentioned sleeves, said first mentioned sleeves being split, the lower two of the 15 first mentioned sleeves being provided with stop lug extensions, and stop members on the relatively rigid member for engagement therewith to limit the downward movement of the relatively rigid member, said relatively rigid member being bent to provide an intermediate portion and offset side wings having apertures, eyelet rivets in the apertures and holding the second mentioned sleeves on the wings, lacing trained through said eyelet rivets, and a tongue simulating loop attached to the upper end of said rigid member.

limit the downward movement of the relatively rigid member, said relatively rigid member being bent to provide an intermediate portion and offset side wings having apertures, eyelet rivets in the apertures for holding the second mentioned sleeves on the wings, lacing trained through said eyelet rivets, and a tongue simulating loop attached to the upper end of said rigid member.

4. In a structure of the class described, two series of sleeves, the sleeves in each series being alined with each other and having ears adapted to be riveted to the upper of a shoe, a relatively rigid member, sleeves fixed to the relatively rigid member, a series on each side thereof, a cord trained through the last mentioned sleeves so that said last mentioned sleeves and the cord may slide in the first mentioned sleeves, said first mentioned sleeves being provided with stop lug extensions, stop members on the relatively rigid member for engagement therewith to limit the downward movement of the relatively rigid member, said relatively rigid member being bent to provide an intermediate portion and offset side wings having apertures, eyelet rivets in the apertures for holding the second mentioned sleeves on the wings, lacing trained through said eyelet rivets, and a tongue simulating loop attached to the upper end of said rigid member.
